UNITED STATES PATENT OFFICE

171,960

TOY TRANSIT

Carl E. Wright, Burbank, Calif.

Application October 1, 1953, Serial No. 27,052

Term of patent 7 years

(Cl. D34—15)

To all whom it may concern:

Be it known that I, Carl E. Wright, a citizen of the United States and a resident of Burbank, California, have invented a new, ornamental, and original Design for Toy Transit, of which the following is a specification, reference being had to the accompanying drawings which form a part hereof:

Fig. 1 is a side elevational view of a toy transit, showing my new design;

Fig. 2 is a rear elevational view thereof;

Fig. 3 is a front elevational view thereof;

Fig. 4 is a top plan view thereof; and

Fig. 5 is a cross-sectional view thereof taken on the line 5—5 in Fig. 1.

I claim:

The ornamental design for a toy transit, substantially as shown.
